CLAIM

I claim the ornamental design for a bathroom hardware support, as shown and described.

DESCRIPTION

FIG. 1 is a perspective view of a bathroom hardware support of the present claimed design;

FIG. 2 is a side view of the bathroom hardware support shown in FIG. 1, the opposite side view being identical thereto;

FIG. 3 is a top view of the bathroom hardware support shown in FIG. 1, the opposite bottom view being identical thereto;

FIG. 4 is a front view of the bathroom hardware support shown in FIG. 1;

FIG. 5 is a perspective view of an alternative embodiment of a bathroom hardware support of the present claimed design;

FIG. 6 is a side view of the bathroom hardware support shown in FIG. 5, the opposite side view being identical thereto;

FIG. 7 is a top view of the bathroom hardware support shown in FIG. 5, the opposite bottom view being identical thereto; and,

FIG. 8 is a front view of the bathroom hardware support shown in FIG. 5.

The rear view of the bathroom hardware support shown in FIG. 1 is plain and unornamented.

The rear view of the bathroom hardware support shown in FIG. 5 is plain and unornamented.

Features shown in broken lines in the drawings are not part of the claim.

1 Claim, 4 Drawing Sheets
